CLAIM

The ornamental design for a fence, as shown and described.

DESCRIPTION

FIG. 1 is a front, right and bottom perspective view of a fence, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a partial enlarged view of an area labeled 8 in FIG. 1 including a gear; and,

FIG. 9 is a partial enlarged view of an area labeled 9 in FIG. 1 including a sliding block.

The broken lines represent portions of the fence that form no part of the claimed design.

The broken boundary lines in FIGS. 1, 8 and 9 represent a portion of the article annotated for enlargement purposes and form no part of the claimed design.

1 Claim, 9 Drawing Sheets
